A. BRAND

MACHINE FOR PRINTING AMPULLÆ

Filed Dec. 9, 1925

UNITED STATES PATENT OFFICE.

ALBERT BRAND, OF MUNICH, GERMANY.

MACHINE FOR PRINTING AMPULLÆ.

Application filed December 9, 1925, Serial No. 74,412, and in Germany February 4, 1924.

This invention relates to a machine for printing ampullæ in which the printing block inked by a slidable inking mechanism is mounted in a printing head designed to execute a reciprocating down and up movement. According to the invention the ampulla, inserted underneath the inking carriage is rolled by this inking carriage over a rubber plate which is preferably elastically mounted and by which the ampulla is printed as the text to be printed on the ampulla has been previously printed as negative upon the rubber plate by the printing block of the printing head.

15 An embodiment of the invention is shown, by way of example, in the accompanying drawing in which—

Fig. 1 shows in plan view a portion of the improved ampullæ-printing machine.

20 Fig. 2 is a side elevation and

Fig. 3 a front elevation.

In the frame of the machine a worm shaft *a* is journaled which drives a spur wheel *b*. From the spur wheel *b* the inking mechanism is driven by an eccentric rod *c*. The inking mechanism is composed of the inking rollers *d* and the rubber plate *e* to which a rotative movement is communicated at every backward movement by a rod *f* fixed on the eccentric rod *c*. A cam *g* projecting from the spur wheel *b* serves to intermittently operate a lever *h* carrying the printing head *i* in which the printing block is mounted. A spring *o* serves to return the lever *h* into its initial position after each operation. The types in the printing block are positive. Under the printing head *i* a rubber plate *k* is arranged onto which the printing block

prints a negative copy of the text at each descending movement of the printing head *i*. The ampullæ are placed by hand under the carriage *l* of the inking mechanism behind the rubber plate *k*. When the carriage *l* moves in forward direction for inking the printing block on the printing head *i* (position shown in dotted lines) the carriage *l* rolls the ampulla over the rubber plate *k* from which the negative print received from the printing block is transferred as positive print onto the ampulla.

The support *m* for the rubber plate *k* is yieldably mounted by means of spiral springs *n* so that slight difference in the cross sections of the ampullæ is accounted for.

I claim:—

A machine for printing ampullæ, comprising in combination with the machine frame a printing head containing positive type, a main driving shaft, means for communicating a reciprocating movement in vertical direction from said main driving shaft to said printing head, a rubber plate underneath said printing head, an elastic support for said rubber plate, an inking mechanism mounted on a carriage, means for communicating to said carriage of the inking mechanisms a forward and backward movement so that an ampulla placed by hand behind said rubber plate is rolled over said rubber plate by the moving carriage of the inking mechanism and the negative copy of the text printed onto said rubber plate by said descending printing head is transferred onto the ampulla.

In testimony whereof I affix my signature.
ALBERT BRAND.
